DESIGN FOR A VASE

Glenn M. Shaw, Lakewood, Ohio, assignor to Eli I. Goulder, Cleveland Heights, Ohio

Application October 23, 1943, Serial No. 111,486

Term of patent 3½ years

(Cl. D29—28)

To all whom it may concern:

Be it known that I, Glenn M. Shaw, a citizen of the United States, residing at Lakewood, in the county of Cuyahoga and State of Ohio, have invented a new, original, and ornamental Design for a Vase, of which the following is a specification, reference being had to the accompanying drawing, forming a part thereof.

Fig. 1 is a perspective view facing the front or wide face of the vase, and Fig. 2 is a side elevation thereof.

I claim:

The ornamental design for a vase, substantially as shown.

GLENN M. SHAW.
